UNITED STATES PATENT OFFICE.

ROMEO WANKMÜLLER, OF BERLIN, GERMANY, ASSIGNOR TO LUFT-VERKEHRS-
GESELLSCHAFT M. B. H., OF CHARLOTTENBURG, NEAR BERLIN, GERMANY.

AIRSHIP.

1,005,097.

Specification of Letters Patent.

Patented Oct. 3, 1911.

Original application filed February 9, 1911, Serial No. 607,469. Divided and this application filed June 26, 1911. Serial No. 635,268.

To all whom it may concern:

Be it known that I, ROMEO WANKMÜLLER, a citizen of the German Empire, and residing at Berlin, German Empire, have 5 invented certain new and useful Improvements in Airships, of which the following is a description.

The present invention relates to that class of balloons described in my pending application Ser. No. 607,469 filed February 9, 10, 1911, of which the present application is a division and in which several auxiliary cars are suspended from the envelop of a dirigible balloon and connected to and adjustable 15 from the main car.

According to the present invention novel means are provided for adjusting not only the height of the auxiliary cars but also their distance apart as regards each other 20 and from the main car.

In order to render the present specification easily intelligible reference is had to the accompanying drawing which represents a diagrammatic end view of a dirigible balloon showing two auxiliary cars and the means for adjusting the same from the main car. The main car 2 is suspended from the balloon proper 1 in the usual manner, while the auxiliary cars 3, 3 are suspended substantially tangentially from the 25 balloon or envelop at each side of the main car by means of a tackle 9 adjustable by means of pulleys 8 and lines 10 from the main car, so as to regulate the vertical 30 height of the auxiliary cars. Hinged to each of the auxiliary cars are rigid bars 4, 4 which are pivoted together at their free 35 ends at 5. A line, wire rope, chain or the

like 11 is attached to the pivot 5 and may be taken in or let out from the car by means 40 of a winch 7.

Obviously, when the parts are in the position illustrated in the drawing and if the pivot 5 is lowered by winding the line 11 on to the drum 6 of the winch the rigid bars 45 4 will force the auxiliary cars 3, 3 farther apart. If, on the other hand, a line 11 is unwound from the drum the weight of the cars 3 will force the pivot 5 upward until the cars have assumed the vertical position 50 by gravity.

What I claim is:—

1. In a balloon the combination of a main car and auxiliary cars suspended from the envelop, rigid connections between the 55 auxiliary cars pivoted together above the main car and means for raising and lowering the pivot of the said rigid connections from the main car.

2. In a balloon the combination of a main 60 car auxiliary cars arranged at each side of the same, rigid links having one end connected to each auxiliary car and the free ends pivoted together, means for raising and lowering the pivot of the said links 65 from the main car, and means for raising and lowering the auxiliary cars bodily also from the main car, substantially as described.

In testimony whereof I affix my signature 70 in the presence of two witnesses.

ROMEO WANKMÜLLER.
